(57) **CLAIM**

The ornamental design for an adaptor for supporting a darkening drape, as shown and described.

DESCRIPTION

FIG. 1 is a top, left side perspective view of an adaptor for supporting a darkening drape with an exemplary darkening drape connected thereto, in the environment of having an exemplary handheld imaging device mounted thereon.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines showing a handheld imaging device mounted on the adaptor for supporting a darkening drape and a darkening drape connected to the adaptor for supporting a darkening drape are provided for the purposes of illustrating environmental structure; whereas all other broken lines in FIGS. 1-7 show portions of the adaptor for supporting a darkening drape. The broken lines showing the aforementioned handheld imaging device, darkening drape, and portions of the adaptor for supporting a darkening drape do not form part of the claimed design.

The light weight lines in the figures show surface contour and material and not surface ornamentation.

The adaptor for supporting a darkening drape is not limited to the scale shown herein.

1 Claim, 7 Drawing Sheets
